United States Patent Office

Des. 180,744
Patented Aug. 6, 1957

180,744

STAND FOR A PORTABLE SEWING MACHINE OR THE LIKE

Robert G. Miller and Kenneth E. Miller, Dalton, Ga.

Application February 17, 1956, Serial No. 40,209

Term of patent 14 years

(Cl. D33—12)

FIG. 1.

FIG. 2.

Figure 1 is a perspective view of a stand for a portable sewing machine or the like, showing our new design; and Fig. 2 is a perspective view thereof in open position. The dotted line indication of a brace element in Fig. 2 is for illustrative purposes only.

We claim:

The ornamental design for a stand for a portable sewing machine or the like, as shown and described.
